UNITED STATES PATENT OFFICE.

FRANZ O. MATTHIESSEN, OF IRVINGTON, NEW YORK.

APPARATUS FOR DECOLORIZING SUGAR-LIQUOR BY FILTRATION THROUGH BONE-BLACK.

SPECIFICATION forming part of Letters Patent No. 335,763, dated February 9, 1886.

Application filed August 20, 1885. Serial No. 174,865. (No model.)

To all whom it may concern:

Be it known that I, FRANZ O. MATTHIESSEN, of Irvington, New York, have invented certain Improvements in Apparatus for Effecting the Decolorization of Sugar-Liquor by Filtration through Bone-Black, of which the following is a specification.

In the process of decolorizing sugar-liquor by filtration through bone-black the bone-black with which the sugar-liquor first acquires contact soonest loses its decolorizing power, or, so to speak, becomes exhausted. Ordinarily the filtering-chamber has to be emptied before the whole of the bone-black contained in it has become exhausted, because the stratum of bone-black with which the sugar-liquor first acquires contact becomes so clogged with impurities that the sugar-liquor cannot pass through it.

The object of my improvement is to provide for a more uniform utilization of the decolorizing power of all the bone-black contained in the filtering-chamber, to which end I provide the filtering-chamber with a stirrer, by the operation of which at the proper time I stir the contents thereof, and thus break up the stratum of bone-black which has been clogged by the impurities, and mix those portions of the mass of bone-black which have become exhausted with other portions which still retain to some extent their decolorizing power.

The accompanying drawings, illustrating apparatus embodying my invention, are as follows:

Figure 1 is a central vertical section of a filtering-vessel in form of a horizontal cylinder supported on rolling bearings and provided with mechanism by means of which it may be rotated upon its longitudinal axis, and also showing a stirrer composed of a horizontal shaft provided with radially-projecting arms and provided with bearings in the end of the filtering-vessel. Fig. 2 is an end elevation showing the worm-gearing for rotating the filtering-cylinder. Fig. 3 is a transverse vertical section on the line xx on Fig. 1.

Referring to the drawings, it will be seen that the filtering-vessel A is a hollow cylinder provided with circumferential flanges or bands a a' a'' , which are engaged in the grooves of two parallel systems of grooved rollers, B b , mounted in suitable bearings in a

substantial frame, C , serving to support the filtering-cylinder A , as shown. One of the flanges a is provided with the teeth d , which are suitably shaped to be engaged by the worm D , mounted in substantial fixed bearings, D' D'' , and provided with a toothed wheel, D'' , or other instrumentality by means of which the worm D can be turned for the purpose of effecting the rotation of the filtering-cylinder A . The filtering-cylinder is provided at the top with an opening, A' , which may, if desired, be closed by the application of the cover A'' . On the side opposite the opening A'' the filtering-cylinder is provided with a series of discharge-cocks, E E , &c., the operating-levers e e , &c., of which are adapted to be engaged by the teeth f f f , &c., of the horizontal bar F , to which a reciprocating sliding motion may be given by means of the hand-lever F' , for the purpose of simultaneously opening or closing the discharge-cocks E E , &c.

In the position in which the parts are represented in the drawings the opening A' is at the top of the cylinder, the discharge-cocks are closed, and their operating-levers hang vertically downward, so that when the filtering-cylinder A is rotated upon its horizontal axis the operating-levers e e , &c., are swung out from between the teeth f f , &c., of the horizontal bar F .

The charge of bone-black required to fill the cylinder A is introduced through the opening A' . For the discharge of the bone-black the cylinder is turned, say, half around, and the cover A'' being removed the bone-black then falls by its own gravity out of the opening A' . The filtering-cylinder is provided with a stirrer consisting of the horizontal shaft G , mounted in suitable bearings, G' G'' , in the opposite ends of the cylinder A , and provided with the radially-projecting arms g g g , &c. The projecting outer end of the shaft G is provided with a crank or other instrumentality—such as the drum-head G'' —provided with radial holes for the reception of bars, by means of which it can be rotated for the purpose of stirring the contents of the filtering-vessel.

The sugar-liquor to be decolorized is introduced into the filtering-chamber A by means of the service-pipe H , and in operation is allowed to remain in contact with the bone-black

contained in the filtering-chamber for any desired length of time, and is then, after having been subjected to the decolorizing influence of the bone-black, discharged by opening 5 the discharge-cocks E. Whenever, owing to the collection of impurities at the top of the mass of bone-black contained in the filtering-chamber, it becomes necessary to do so, the stirrer is rotated, thus breaking up the stratum 10 of bone-black at the top which has become highly charged with impurities, and mixing it with the remainder of the bone-black, the filtering operation being continued by the introduction into and discharge from the filtering-chamber of additional quantities of sugar-liquor until the decolorizing power of the bone-black contained therein has been so far exhausted as to render necessary the discharge 15 of the filtering-chamber and the introduction 20 into it of a supply of fresh bone-black.

I claim as my invention—

1. In apparatus for decolorizing sugar-liquor by the process of filtration through bone-black, a rotatable cylindrical filtering-chamber supported in horizontal bearings and provided with an opening in its surface through 25 which bone-black can be introduced into and

discharged from it, and also provided with a series of drain-cocks arranged in a line parallel with its axis, in combination with a stirrer 30 and means for operating the same for stirring the bone-black contained in the filtering-chamber during the progress of the operation of decolorizing sugar-liquor which has been introduced into the filtering-chamber.

2. The filtering-cylinder A, containing a stirrer, G, and provided with an opening, A', in its surface and with suitable drain-cocks, and provided with two or more circumferential flanges, in combination with two parallel series 40 of rollers mounted in horizontal bearings, and having grooved faces for engaging the said flanges, and means for rotating the filtering-cylinder, as and for the purpose set forth.

3. The filtering-cylinder A, containing the 45 stirrer G, and provided with the series E of drain-cocks, each having an operating-lever, e, in combination with the reciprocating bar F, provided with the teeth f, &c., as and for the purpose set forth.
